US00D571766S

(12) **United States Design Patent**
Christiansen et al.

(10) **Patent No.:** **US D571,766 S**
(45) **Date of Patent:** **** Jun. 24, 2008**

(54) **HANDSET**

(75) Inventors: **Thomas Christiansen**, Kobenhavn (DK); **Anton Fahlgren**, Copenhagen (DK)

(73) Assignee: **Nokia Corporation**, Espoo (FI)

(**) Term: **14 Years**

(21) Appl. No.: **29/280,450**

(22) Filed: **May 29, 2007**

(30) **Foreign Application Priority Data**

Nov. 28, 2006 (FI) M20060220

(51) **LOC (8) Cl.** **14-03**

(52) **U.S. Cl.** **D14/138**

(58) **Field of Classification Search** D14/137, D14/138, 147, 191, 218, 247-248, 341-347, D14/496; D10/65, 78, 104; D13/168; D18/7; 455/90.3, 556.1, 566, 575.1, 575.3, 575.4
